UNITED STATES PATENT OFFICE.

REUBEN LICHTER AND LEWIS LEWENHOFF, OF NEW YORK, N. Y.

CARBONATING APPARATUS.

1,052,599.

Specification of Letters Patent. Patented Feb. 11, 1913.

Application filed April 23, 1912. Serial No. 692,723.

To all whom it may concern:

Be it known that we, REUBEN LICHTER and LEWIS LEWENHOFF, a subject of the Czar of Russia and a citizen of the United States, 5 residing at New York, county and State of New York, and in New York, borough of Brooklyn, county of Kings, and State of New York, respectively, have invented a certain new and useful Improvement in 10 Carbonating Apparatus, of which the following is a full, clear, and exact specification.

This invention relates to a class of tanks or containers adapted to be used for manufacturing and dispensing carbonated waters.

Our invention has for its object primarily to provide a form of tank, or container designed to be employed in conjunction with soda fountains, or similar apparatus for 20 carrying a supply of carbonated water to be dispensed therefrom for drinking purposes, and wherein is employed a filter for clarifying the water as it is admitted into the tank and before the water is charged 25 with gas, thereby dispensing with the requirement of using a special filtering apparatus.

Another object of the invention is to provide the tank with a lining which will 30 not rust or corrode from the action of the carbonated water thereon; and a further object of the invention is to provide a form of tank which is susceptible of being made so as to be very durable, in order to safely 35 withstand a high pressure of the carbonating gas, but which is comparatively light in weight.

A practical embodiment of the invention is represented in the accompanying drawing 40 forming a part of this specification in which similar characters of reference indicate corresponding parts in all the views, the said invention being more fully described hereinafter and then pointed out in 45 the appended claims.

In the drawings, Figure 1 is a longitudinal vertical section through one form of soda fountain tank embodying our invention. Fig. 2, is a section taken on the line 50 II-II of Fig. 1. Fig. 3 is a vertical side view, partly in section and partly broken away, of the filter employed in conjunction with the tank. Fig. 4 is a top plan of one of the funnel-shaped partitions. Fig. 5 is a sectional view, partly in detail, of the valve of the tank, and Fig. 6 is a fragmentary

view, partly in section, showing the manner of fastening the sections of the body of the tank together.

The tank 10 has a body, or shell 11 composed of two sections, or members 12 and 13 which are somewhat similar in shape, each being parabolic in form or substantially U-shaped in cross section. Upon the opposed edge of the open end of each of the sections, or members 12 and 13 is an annular flange 14 and 15, and circumscribing a part of the curved end of the section 13 is the usual flange 16 which serves to support the tank when disposed in a vertical position. Through each of the annular flanges 14 and 15 are a number of corresponding spaced openings 17 and 18, and to provide an air-tight and water-tight joint between said sections a packing, or gasket, as 19, is inserted between the opposed surfaces of said annular flanges.

In order to permit the flanges 14 and 15 to be firmly secured for holding the sections 12 and 13 together a ring 20 is 80 guided over the section 13, and disposed so as to abut against the underside of the flange 15. A second ring 21 having an annular depending flange 22 upon its outer edge is guided over the section 12, 85 and disposed upon the top surface of the flange 14 so that the depending flange of the ring 21 will overlap the peripheral edge of the annular flanges 14 and 15. Through the rings 20 and 21 are spaced openings 23 90 and 24 which are in alinement with the openings of the annular flanges 14 and 15 so that bolts, or the like may be passed therethrough for tightly fastening the parts 95 together.

As is incident to the usual form of soda fountain tanks, we prefer to make both of the sections 12 and 13 of the body 11 of seamless steel which may be formed by any well known stamping process so as to be sufficiently durable to withstand a high pressure, but will be comparatively light in weight. Serving to prevent the inner surface of the tank from rusting or corroding, both of the sections 12 and 13 of the body 100 11 is lined with aluminum, or other material, as 25, which is not susceptible of being affected by contact with water, or carbonaceous gases.

Within the body 11 of the tank is a device 110 26 adapted to be employed for filtering water admitted to the tank through the me-

dium of a pipe, as 27, and a valve 28 of any suitable source of supply. The device 26 has a casing 29 of a circular shape, and which is preferably made of aluminum. In 5 the lower portion of the casing 29 is a perforated plate 30, and within said casing are a plurality of superimposed, funnel-shaped members, or partitions 31 whereby chambers or inclosures 32 are provided. The wall of 10 each of the funnel-shaped partitions are provided with spaced perforations 33, and the large open end of each of said partitions is covered by a cap 34 which also has a plurality of spaced perforations 35 there- 15 through. The funnel-shaped partitions are positioned so that the apex of one rests centrally upon the perforated cap of the partition underneath it, and in the chambers, or inclosures 36 thus formed is a required 20 quantity of filtering material 37, such as small particles of stone, or other suitable substances. Centrally of the top of the casing 29 is a neck 38 whereby an inlet 39 is provided. The neck 38 is exteriorly threaded 25 so that a nut 39^a may be screwed thereon for holding the filtering device 26 against displacement within the body 11 when said neck is disposed through an opening 40 pro- 30 vided in the top of the section 12 of the body, and to provide a water-tight joint be- 35 tween the top of the casing 29 and the lining 25 is a packing, or gasket 41. Centrally through each of the funnel-shaped partitions 31 is an opening 42 so that all of the 40 openings will be in alinement when the partitions are assembled, as shown in Fig. 1, and guided through said openings is a pipe 43 which is of sufficient length to extend 45 through the filtering device to nearly the inner surface of the bottom of the tank. The casing 29, the funnel-shaped partitions 31, and the pipe 43 are preferably made of aluminum, though any other non-rustable and non-corrosive material may be used. 50 The neck 38 of the casing 39 of the filter is interiorly threaded for reception of the threaded end of a fitting or coupling 44. The fitting or coupling 44 may be of the 55 usual or any preferred type having a body 45, and in the lower part of said body is a vertical passage 46. Transversely through the body 45 of the valve are oppositely disposed passages 47 and 48 which communicate with the passage 46. The transverse 60 passage 47 serves as an inlet for admission of the gas with which the water in the tank is charged and also serves as an outlet for the carbonated water when ready to be dispensed. The mouth of the transverse pas- 65 sage 47 may be closed by a cap 49, and in the transverse passage 48 is a rotatable needle valve, or cock 50 adapted to be revolved by a hand-wheel 51. The cock 50 is adapted to control the opening and closing of the pas- 70 sage 47, and thereby also controls the ver-

tical passage 46. Through the body 45 from its top to its bottom is a passage 52. In the lower part of the passage 52 is a tube 53, and in the upper part of said passage may be placed a nipple to permit the pipe 27 to be connected to the valve whereby water from its source of supply may be delivered to the filtering device 26 through the passage 52 and through the tube 53. The water will then be filtered by flowing through 75 the perforated funnel-shaped partitions 31, through the clarifying material 37, and into the tank. After the passage 52 is suitably closed, and the cap 49 is removed from the body of the valve 44, the carbonating gas is admitted through the transverse passage 47, through the vertical passage 46 and through the pipe 43. The water is charged with the gas by agitation in the usual manner of rocking the tank while the gas is being admitted thereinto. The tank is then closed by the cock 50 and the carbonated water may afterward be dispensed by rotating the cock 50 to open the passages 46 and 47 whereby the pressure of the carbonated water will force it to flow from the tank through the pipe 43 and through the passages 46 and 47. 80

In the foregoing description we have embodied the preferred form of our invention, but we do not wish to be understood as limiting ourselves thereto, as we are aware that modifications may be made therein without departing from the principle, or sacrificing any of the advantages of this invention, therefore we reserve to ourselves the right to make such changes as fairly fall within the scope thereof. 85

Having thus described our invention, we claim as new and desire to secure by Letters Patent:— 90

1. The combination with a soda fountain tank having a suitable outer casing and suitable means for admitting water, and other liquid, or gas thereto and for withdrawing said liquid, of a cylindrical casing having a removable contracted neck adapted for connection with the tank, said casing having a perforated bottom plate, a plurality of removable funnel-shaped perforated members in superposed arrangement therein, said funnel-shaped members having their top portions inclosed by a perforated cap, each of said members having an opening in the apex thereof, and a removable pipe longitudinally disposed through the tank and through the openings in the apices of the said funnel-shaped members and through one of the perforations of the cap, and the apex of the lowest member of the series having its apex seated in an opening provided in the central part of the bottom plate of the said casing, and said pipe having one of its ends extending beyond the apex of the said lowest funnel-shaped members, whereby 100

liquid substance may be withdrawn through said pipe from below the said cylindrical casing.

2. In a device of the character described, 5 the combination with a suitable fitting having an inlet and outlet port, of a cylindrical casing, said casing having a neck portion removable thereon for connecting the casing with the fitting, a bottom plate in the lower 10 end of the casing, said bottom plate having a plurality of spaced perforations and a larger central opening therethrough, a removable funnel-shaped member disposed within the casing, said funnel-shaped member 15 having a tubular portion upon its apex and which is seated in the central opening of the bottom plate of said casing, said funnel-shaped member having a plurality of spaced openings in its wall, a cap inclosing 20 the upper end of the casing, said cap having also a plurality of spaced openings therethrough, and having also a central opening, and removable pipe having one end connected to the fitting for the discharge of 25 liquid therethrough, said pipe being disposed through the large opening of the cap of the member and through the opening in the apex thereof, substantially as shown and described.
3. In a device of the character described, 30 having an exterior casing and a fitting provided with inlet and outlet ports, said exterior casing being provided with an inner lining of aluminum, the combination of a cylindrical casing having a neck portion 35 removably fitted therein and adapted for connection with the fitting of the exterior casing, a perforated plate in the bottom of the cylindrical casing and having a central 40 opening therethrough, a plurality of removable funnel-shaped members, each having a cap over its large end and each having a tubular member provided upon its apex, 45 said funnel-shaped members and the caps thereof, each having spaced perforations therethrough, and said funnel-shaped members being superposed one above the other, the first having the tubular member extending 50 through the central opening in the bottom plate of the cylindrical casing and each

of the other superposed funnel-shaped members being arranged with its tubular member seated in the central opening of the cap of the adjoining funnel-shaped member, whereby a plurality of chambers are provided for 55 clarifying substances between the inner walls of the cylindrical casing and the walls of said funnel-shaped members, said funnel-shaped members each being traversed by a removable pipe, one end of the pipe extending below the apex of the lower funnel-shaped member, whereby liquid may be withdrawn from the exterior casing, substantially as shown and described.

4. In a device of the character described, 60 in combination, an exterior tank having an inlet and outlet and having an inner lining of aluminum, a cylindrical casing having a solid side wall and a perforated end wall at one end thereof, said perforated end wall being provided with a central opening and having a normally open opposite end, a suitable neck-portion removably fitting within the open end and having screw-threaded inner and outer peripheral surfaces, whereby it may be connected with the exterior tank, a plurality of funnel-shaped members, each having perforated walls and a perforated cap, said cap having a central 65 opening therethrough, said funnel-shaped members being adapted to be removably disposed in superposed order one upon the other within the tank whereby a plurality of concentric funnel-shaped repositories for filtering substances are provided within the 70 cylindrical casing and around the funnel-shaped members, and a removable pipe extending through the central portion of the said cylindrical casing, and through each of the central openings of the funnel-shaped 75 members so as to extend to the lower end of the tank, substantially as shown and described.

This specification signed and witnessed this twenty-second day of April A. D. 1912. 80
